UNITED STATES PATENT OFFICE.

HENRY W. BUHLER, OF BOSTON, MASSACHUSETTS.

COKE-OVEN.

1,319,839.

Specification of Letters Patent. Patented Oct. 28, 1919.

Application filed January 13, 1917. Serial No. 142,167.

To all whom it may concern:

Be it known that I, HENRY W. BUHLER, a citizen of the United States of America, residing at Boston, county of Suffolk, State 5 of Massachusetts, have invented certain new and useful Improvements in Coke-Ovens, (Case A,) of which the following is a specification.

My invention relates to heating apparatus 10 generally and is designed to produce uniform heating effects over the wall surfaces of combustion chambers of large dimensions. While my invention is capable of general application its most advantageous specific 15 embodiment now known to me is found in its application to the heating of coke ovens. Modern coking practice is tending more and more toward the employment of high coking chambers of ten or eleven feet or more 20 in vertical dimension, and to heat these correspondingly high vertical flues are formed in the chamber walls. The even heating of these coking chambers so as to produce uniform coking conditions at all levels therein 25 requires a lengthening of the flame of combustion in said flues so as to subject all portions of the flue walls to uniform heating effects. Combustion is usually produced by introducing fluid fuel, such as gas, together 30 with air through passageways in one of the flue walls (generally the lower wall or floor) and the streams of fuel and air so produced are projected upward through the flue or combustion chamber, being ignited by the 35 heat of the walls and the combustion already going on in the flue. With the ordinary form of single burner the combustion begins at or near the burner mouth and is completed within a comparatively restricted zone above 40 said mouth so that no active generation of heat takes place in the upper part of the flue. Consequently the heating of the upper zone of the adjacent oven or retort is only that caused by radiation from the gradually cool- 45 ing gases of combustion, while the lower zone may be subjected to injurious overheating by the rapid, localized combustion taking place in the lower part of the flues near the burner mouth.

50 I have discovered that the initial rapidity or activity of combustion at and near the burner mouth can be decreased and the completion of combustion delayed until the rising currents of fuel and air reach the upper 55 portion of the flues, by causing the fuel to

enter the flue at a plurality of points at widely varying distances from the air inlet instead of admitting all the fuel at one point as heretofore, through an ordinary circular burner nozzle. The best form of apparatus 60 at present known to me embodying my invention is illustrated in the accompanying drawings in which—

Figure 1 is a vertical cross section through a coke oven with parts broken away and 65 others omitted.

Fig. 2 is a horizontal section taken on line 2—2 of Fig. 1, and

Fig. 3 is a similar view showing a modification. 70

Throughout the drawings like reference characters indicate like parts. 1, 1, represent the ovens or retorts to be heated, and 3, 3, the vertical heating flues or combustion chambers formed in the oven walls, 2, 2. 75 Preferably the flues have a vertical dimension greatly in excess of their horizontal dimensions, though their horizontal cross sections increase progressively upward as indicated by the terracing of their side walls 80 at 19, 19. Access to, and observation of conditions in, the heating flue may be had through channel 17 in the top wall thereof, controlled by cover 18.

The fuel and air for combustion enter 85 each flue 3, through passageways in one wall (usually the bottom wall or floor, as shown) and preferably, as shown, the axes of these passageways are parallel one to another and to the longest dimension of the flue. 12, 12, 90 represent chambers of air supply in which is maintained an atmospheric pressure greater than that in flues 3, 3. Usually this difference between atmospheric pressures is produced and maintained by chimney draft, 95 but any equivalent means can be employed. The excess of pressure in 12, 12, however produced, forces air therefrom into flues 3, 3, through passageways 15, 15, and laterally extending branches 13, 13. In the inner portion 100 of each passageway 15, which is of reduced diameter, is preferably located a removable nozzle 14, of highly refractory material which has a flanged outer end 20, resting in the outer portion of passageway 15, 105 which is of larger diameter. The remainder of the passageway 15, is filled with plug 16, which has its inner end partly cut away at 21, so as to register with the mouth of branch passageway 13, and 110

afford communication with the bore of nozzle 14. The air may of course be pre-heated by any usual method.

The fuel is introduced through the same 5 wall as is the air, but at a plurality of points, as by a plurality of burners. I have shown two burners. The burner nearest the air inlet is composed of tube 6, and removable tip or nozzle 4, located in passageway 8. 10 The other is composed of tube 7, and removable tip or nozzle 5, located in passageway 9. 10, and 11, are valves controlling the flow of gas through tubes 6, and 7, from gasometer 22, or other source of supply of 15 fluid fuel under pressure. Tubes 6 and 7, may be made of iron or other cheap, strong material, while nozzles 4 and 5 are made of more highly refractory material such as fire brick. These nozzles do not project into the 20 flue 3, but are withdrawn a slight distance into passageways 8 and 9, being hooded thereby.

In operation streams of air and gas are 25 projected into flues 3, 3, parallel to the longest dimensions thereof, and combustion by combination of the air with fuel from burner nozzle 4, nearest the air inlet, begins at or near the burner nozzle in each case. As the 30 flames shoot upward the gas from the more remote burner nozzle 5, gradually mixes with the burning gases and feeds the flames, sustaining and continuing the combustion and prolonging the flames until the extreme 35 upper zones of the flues are reached. The increasing cross sections of the upper flue zone due to steps or terraces 19, 19, accommodate the expanding gases of combustion as the flames are fed by fuel supply from supplemental burner 5, in each flue. 40 The same general principle of operation may be conserved by substituting one long flat burner 23, shown in Fig. 3 for the plurality of circular burners shown in Fig. 2. Combustion then begins in the lower zone at 45 the edge of the flat ribbon of gas discharged into the flue adjacent to the air inlet and spreads progressively to the farther edge as the upper flue zones are reached.

The best results are, however, attained by 50 having a plurality of separate fuel inlets arranged in an approximately straight line, and with the air inlet located at one end of that line, as shown in Figs. 1 and 2.

The advantages of my invention comprise 55 (in addition to the extended volume of the combustion zone) the prolongation of the life of the burners by sinking or hooding the tips thereof some distance within the orifices of the inlet passageways of the walls, where- 60 by they are partly protected from the heat in the combustion chamber, the ease of access to, and removal of, the removable tips both for burners and air supply connections, and the cheapness and convenience of the

interchangeable unit system of air and fuel 65 conduits and nozzles shown and described.

I wish it understood that various changes can be made in the details of construction shown and described without departing from the substance of my invention so long 70 as the general principles of operation and coaction of parts herein set forth are preserved.

Having described my invention, I claim:

1. In a heating apparatus the combination, with a combustion chamber, of an air inlet in one wall thereof, and a plurality of fuel inlets located on one side of the air inlet, all of said air and fuel inlets being arranged in a substantially straight line, and so 80 as to discharge their contents in parallel directions, into the zone of combustion.

2. In a heating apparatus the combination, with a combustion flue of considerable depth relative to its horizontal dimensions, 85 of an air inlet and a plurality of fuel inlets arranged in a substantially straight line at the bottom of the flue, the air inlet being at one end of the line.

3. In a heating apparatus the combination with a combustion flue of considerable depth relative to its horizontal dimensions, of an air inlet and a plurality of fuel inlets in the bottom of the flue, one of the fuel inlets being closer than another to the air 95 inlet.

4. In a heating apparatus the combination, with a combustion flue of considerable depth relative to its horizontal dimensions, of a vertical air inlet passageway entering 100 the bottom of the flue near one side wall, and two vertical fuel inlets also in the bottom of the flue, one of which is much nearer than the other to the air inlet.

5. In a heating apparatus the combination, with a combustion chamber having one dimension longer than the other two dimensions, of an air inlet passageway through one wall the axis of which is substantially parallel to the longest dimension of the 110 chamber, a plurality of fuel inlet passageways in said wall the axes of which are parallel to that of the air inlet passageway and which are located at different distances from the air inlet, and means for forcing streams 115 of combustible fluid and of air through the respective passageways into the combustion chamber.

6. In a heating apparatus the combination, with a combustion chamber having one 120 dimension longer than the other two dimensions, of an air inlet passageway through one wall the axis of which is substantially parallel to the longest dimension of the chamber, and means for forcing fluid fuel 125 into the combustion chamber through the same wall at a plurality of points located at widely varying distances from the air inlet,

7. In a heating apparatus the combination, with a combustion chamber having a straight main air inlet passageway in one wall with a laterally extending branch, of a plug for the outer portion of said main passageway having a partly cutaway portion at its inner end adapted to register with the mouth of the branch passageway when the plug is in position and a removable nozzle 10 adapted to rest in the inner end of the main passageway on the partly cutaway end of the plug.
8. In a heating apparatus the combination, with a combustion chamber having a straight main air inlet passageway in one wall of reduced diameter at and near the orifice and a laterally extending branch from the outer portion of larger diameter, of a removable nozzle in said passageway mainly lying in said portion of reduced diameter 20 but having a flanged end resting in the portion of larger diameter, and a plug filling the remainder of the passageway having a cutaway portion at its inner end registering with the mouth of the branch passageway 25 and communicating with the bore of the nozzle.
9. In a heating apparatus the combination, with a combustion flue of considerable depth relative to its horizontal dimensions, 30 of an air inlet and a plurality of fuel inlets in the bottom of the flue, one of the fuel inlets being closer than another to the air inlet, the cross section of the combustion flue being greater in its upper portions than in 35 its lower portions.

HENRY W. BUHLER.
